UNITED STATES PATENT OFFICE

HERBERT E. WHITE, OF YOUNGSTOWN, OHIO, ASSIGNOR TO TRUSCON STEEL COMPANY, OF YOUNGSTOWN, OHIO, A CORPORATION OF MICHIGAN

WEATHER STRIP FOR SLIDING METAL SASH

Application filed November 27, 1928. Serial No. 322,288.

This invention relates to an improved weatherstrip particularly adapted for use in connection with metal sash.

A primary object of the invention is to provide a novel metal weatherstrip to be used on sliding sash. While metal weatherstrips have been heretofore employed in connection with the casement type sash, nevertheless, strips intended for that purpose are not conveniently adaptable to sliding sash. In that connection, the invention contemplates the provision of a simple and practical form of self-secur ing weatherstrip which may be readily fitted to the part of the sliding sash which fits in the window frame, and not only provides a weather-proof joint, but at the same time takes up the play between the sash and the guideway in the frame to prevent rattling of the sash while at the same time permitting it to slide freely under all conditions of use.

A further object of the invention is to provide a metal weatherstrip for sliding sash which is provided with means for assisting in the guiding of the sash during its sliding movement. That is to say, it is proposed to provide a portion of the strip with a part which parallels the guideway in the window frame so that as the sash is moved up and down the said part will act to limit the side motion of the sash.

With the above and other objects in view which will more readily appear as the nature of the invention is better understood, the same consists in the novel construction, combination and arrangement of parts herein-after more fully described, illustrated and claimed.

A preferred and practical embodiment of the invention is shown in the accompanying drawings, in which:

Figure 1 is a detail elevation of a portion of a metal sash and window frame having the present invention applied thereto.

Fig. 2 is a horizontal cross-sectional view taken on the line 2-2 of Fig. 1.

Fig. 3 is a detail perspective view of the improved weatherstrip.

Similar reference characters designate cor-

responding parts throughout the several figures of the drawings.

According to the embodiment of the invention shown in the drawings, the present weatherstrip includes a body designated generally as A and having an attaching portion B at one side thereof and a weather-flange C at the opposite side thereof.

As will be observed from Fig. 3, the securing portion B of the strip includes the resilient flange 1 which is spaced from the body A but connected therewith by the web 2 thereby to provide means for receiving and embracing the frame F of the sash S as shown in Fig. 2.

The weather-flange C at the opposite side of the body includes a resilient leaf portion 3 whose resiliency and hinge-like connection with the body is increased by the provision of the loop or rib 4. This rib constitutes one of the distinctive features of the invention, and is of special importance in a strip for sliding sash since it acts as a stop or abutment for limiting the side movement of the sash when it is raised and lowered in the window frame.

As will be observed from Fig. 2 of the drawings, the strip is applied to the frame F of the sash by fitting the yielding securing portion B over the portion of the frame which projects through the guideway G in the window frame W while the body portion A snugly fits the outer face of the sash frame and the loop which forms the rib 4 is positioned substantially in the angle formed between the sash frame and the window frame thereby to act as a stop and prevent undue side motion of the sash during its movement.

The weather-flange 3 is compressed in the space between the guideway and the body A of the strip thereby to close the gap and keep out air, thus making a tight fit between the outer side of the sash in the window frame, and without exposing the strip to view from the inside of the window. As previously indicated the resilient weather-flange C also prevents the rattling of the window since it yieldingly presses the frame F against one side of the guide at all times. Thus, the sash is not only steadied and balanced in its sliding movement by the yielding flange 3 and the rib 4 but a practical weather-proof joint is

formed which not only keeps out air and water at the sides of the window but also acts as a part of the guiding means for the sash.

Another feature of the invention resides in the relationship of the rib 4 to the securing portion B when the same is applied to the sash. As will be observed from Fig. 2 the securing or clip portion B is fitted over the edge of the frame F in one direction while the rib being on the other side of the window frame which forms a part of the guide, acts as a lock for preventing the disengagement of the securing or clip portion B from the edge of the window frame. Thus, it is impossible for the strip to accidentally become displaced from the edge of the sash after it has been once applied.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:—

1. A weatherstrip for sliding metal sash comprising in combination with a guideway for the sash, of a metal strip doubled upon itself to provide a sash embracing portion and a guideway engaging portion, said guideway engaging portion including a rib for limiting the side movement of the sash.

2. In a weatherstrip for sliding sash, the combination with the window frame having a guideway and a sash member slidably therein, of a weatherstrip having means for engaging the sash and a resilient flange portion having means for closing the guideway and also having means for limiting the side movement of the sash.

3. In a weatherstrip for sliding metal sash, the combination with the window frame having a guideway for the sash, of a resilient strip having a channel portion at one edge for engaging with the sash and an out-turned resilient weather-flange for engaging with one side of the guideway, and a rib formed on said flange for limiting the side movement of the sash in the guideway and also constituting a lock for preventing accidental disengagement of the strip from the sash during the sliding movement thereof.

4. In a weatherstrip for sliding metal sash, the combination with a window frame having a guideway, of a resilient strip comprising a body adapted to flushly engage one side of the sash and having reversely related flange portions at opposite sides thereof respectively forming a sash embracing portion and a guideway engaging portion, and a rib formed at the junction of the body and the said flange portion which engages the guideway.

5. In a weatherstrip for sliding sash the combination with the window frame having a guideway and a sash member slidable therein, of a weatherstrip having means for engaging the sash and a resilient flange portion extending between the sash and the window frame and having means for limiting the side movement of the sash.

6. In combination, a slotted sash frame, a sash stile slidably engaged in the slot in said sash frame, a weatherstrip mounted on said sash stile within the sash frame and extending through said slot exteriorly of the sash frame, said weatherstrip having a bead formation outside the sash frame for cooperation with the sash frame to limit inward lateral movement of the sash relative to the sash frame, said bead formation having a free edge portion disposed at the side of the bead remote from the sash frame.

7. In combination, a slotted sash frame, a sash stile slidably engaged in the slot in said sash frame, a weatherstrip mounted on said sash stile within the sash frame and extending through said slot exteriorly of the sash frame, a bead formed along one side of said strip outside the sash frame for cooperation with the frame to limit inward lateral movement of the sash relative to the sash frame, said bead having a free edge portion disposed at the side of the bead remote from the sash frame, and a stiffening flange at the free edge portion of said bead.

In testimony whereof I hereunto affix my signature.

HERBERT E. WHITE.
